UNITED STATES PATENT OFFICE.

JOHN R. CLOVER, OF ENID, OKLAHOMA.

TOWEL CABINET.

Application filed August 23, 1927. Serial No. 214,738.

This invention relates to improvements in towel cabinets, and the primary object of the invention is to generally simplify and improve devices of this kind so as to meet with 5 all of the requirements for a successful commercial use.

A further object is to provide an improved towel cabinet which is simple and compact in construction, and efficient and reliable in operation.

A still further object is to provide a towel cabinet having an improved guiding and feeding means which will withdraw the soiled portion of the towel proportionately with the 10 supply of the clean portion.

Other objects will become apparent as the nature of the invention is better understood, and the same consists in the novel form, combination and arrangement of parts herein- 15 after more fully described, shown in the accompanying drawings and claims.

In the drawings, wherein like reference characters indicate corresponding parts throughout the several views,

25 Figure 1 is a front elevational view of a towel cabinet constructed in accordance with the present invention,

Figure 2 is a vertical section on line 2—2 of Figure 1,

30 Figure 3 is an enlarged horizontal section on line 3—3 of Figure 2,

Figure 4 is a perspective view of the removable guide plate,

35 Figure 5 is a view similar to Figure 2 of a slightly modified form of the invention, and

Figure 6 is an enlarged horizontal section on line 6—6 of Figure 5.

Referring more in detail to the drawings, the present towel cabinet embodies a casing 5 which is preferably of general rectangular shape and formed at its upper end with a forwardly projecting portion 6 which overhangs a towel space in front of the lower portion 7 of the casing and prevents dirt and dust from 40 falling onto the towel.

The upper portion of the casing preferably has a front opening closed by a door 8 which may have an exterior mirror 9, and arranged within the top of this upper casing portion is 45 a shelf 10 upon which may be placed a comb and brush and like toilet articles.

Within the upper casing portion and upon the back thereof below the shelf 10 is a suitable open top receptacle or basket 11 for reception of the clean toweling, and extending 50 forwardly and downwardly from the upper

edge of the front wall of the receptacle 11 is a transverse guide plate 12 downwardly over which the towel is fed from said receptacle to and around the front side of a feed roller 13. 60 The feed roller 13 is journaled transversely of the casing within the bottom of the projecting upper portion 6 and in front of the lower part of receptacle 11, and this roller has a roughened or other suitable friction surface. 65 In order to confine the towel on the plate 12 for being properly fed thereover to the roller 13, a further transverse guide plate 14 is removably mounted in any suitable manner in spaced parallel relation to and in front of said 70 plate 12. The plate 14 is removable to facilitate positioning of the towel behind the same, and as shown, it may have end flanges 15 adapted to flatly engage the side walls of the casing and provided with bayonet slots 16 for 75 detachable engagement with headed pins 17 carried by said side walls, the slots extending into the ends of the plate 14 to permit forward removal of the latter.

Provided in the bottom of the projecting 80 casing portion 6 are transverse slots 18 and 19 respectively disposed substantially below the front and rear sides of roller 13, and extending upwardly from the front side of slot 18 is a resilient plate 20 which conforms to the 85 roller 13 and yieldingly presses the towel into engagement with the front side of the latter. In a like manner, a resilient plate 21 projects upwardly from the rear side of slot 19 and conforms to the roller 13 to yieldingly press 90 the towel into engagement with the rear side of the latter.

As shown in Figures 2 and 5, the towel T is fed downwardly between the guide plates 11 and 14, around the front side of roller 13, and 95 downwardly through slot 18 where it is formed into a loop in front of the lower casing portion 7 and passed upwardly through slot 19 between the rear side of roller 13 and the presser plate 21. The towel is then fed into 100 the lower portion 7 of the casing by being passed rearwardly and downwardly over a rearwardly and downwardly directed extension 22 of plate 21. Thus, when the roller 13 is turned in the proper direction, the soiled 105 portion of the towel will be withdrawn and deposited in the casing portion 7 and the clean portion of the towel will be proportionately fed through slot 18 from the receptacle 11. The rotation of roller 13 may be effected by 110 pulling downwardly upon the front member of the looped towel portion, or by operating

a handle or crank 23 fastened on a projecting end of the shaft of roller 13.

Means is provided to prevent the towel from winding upon roller 13 after passing the presser plate 20 so that the towel will properly pass down through slot 18. This means consists of a plurality of fingers 24 projecting upwardly at the rear of slots 18 and into peripheral grooves 25 formed in the roller 13. In a like manner, means is provided to prevent the towel from winding upon the roller 13 after passing the presser plate 21, and to direct the towel rearwardly away from the roller over the extension 22. The latter means may embody depending fingers 26 on the lower front portion of receptacle 11 projecting into the grooves 25 as in Figures 2 and 3, or as shown in Figures 5 and 6 it may embody a plurality of thin endless belts 27 passing about the roller 13 in spaced relation and about a smaller idler roller 28 journaled transversely of the casing 5 rearwardly of roller 13 and extension 22. The belts may engage in other peripheral grooves in roller 13, but when made thin they may merely pass about the roller, as shown, and aid in feeding the toweling. The lower casing portion 7 has an opening closed by door 29 to permit removal of the soiled toweling.

From the above, it will be seen that the number of movable parts has been reduced to a minimum, and that the construction is of a generally durable and compact character so as to not readily get out of order.

As the general manner of using devices of this kind is well known, further explanation thereof is deemed unnecessary.

Minor changes may be made without departing from the spirit and scope of the invention as claimed.

What I claim as new is:—

1. In a towel cabinet, a casing including an upper portion having a forwardly projecting part and a lower portion to receive soiled toweling, a receptacle for clean toweling in the rear of said upper portion of the casing, said forwardly projecting part of the casing having spaced transverse front and rear slots in the bottom thereof, a roller journaled in the lower portion of said forwardly projecting part of the casing between said slots, means to press the toweling against the front side of said roller before passing down through the front slot, means to press the toweling against the rear side of said roller after passing up through the rear slot, and means to direct the toweling rearwardly and downwardly from the rear side of said roller into said lower portion of the casing.

2. In a towel cabinet, a casing including an upper portion having a forwardly projecting part and a lower portion to receive soiled toweling, a receptacle for clean toweling in the rear of said upper portion of the casing, 65 said forwardly projecting part of the casing having spaced transverse front and rear slots in the bottom thereof, a roller journaled in the lower portion of said forwardly projecting part of the casing between said slots, 70 means to press the toweling against the front side of said roller before passing down through the front slot, means to press the toweling against the rear side of said roller after passing up through the rear slot, and 75 means to direct the toweling rearwardly and downwardly from the rear side of said roller into said lower portion of the casing, said means to press the toweling against the front and rear sides of said roller embodying resilient presser plates projecting upwardly from the bottom of the forwardly projecting part of the casing at the front of the front slot and at the rear of the rear slot.

3. In a towel cabinet, a casing including an upper portion having a forwardly projecting part and a lower portion to receive soiled toweling, a receptacle for clean toweling in the rear of said upper portion of the casing, 80 said forwardly projecting part of the casing having spaced transverse front and rear slots in the bottom thereof, a roller journaled in the lower portion of said forwardly projecting part of the casing between said slots, 85 means to press the toweling against the front side of said roller before passing down through the front slot, means to press the toweling against the rear side of said roller after passing up through the rear slot, and 90 means to direct the toweling rearwardly and downwardly from the rear side of said roller into said lower portion of the casing, a second roller journaled in the upper portion of the casing beneath said receptacle and rearwardly of said first named roller, said first 95 named roller having a plurality of spaced peripheral grooves, spring fingers projecting upwardly from the bottom of said forwardly projecting part of the casing into the grooves of said first named roller for preventing the toweling from winding onto the latter in passing downwardly to the front slot, and a plurality of endless belts passing about said first and second named rollers to prevent 100 winding of the toweling onto the first named roller after passing upwardly through the rear slot.

In testimony whereof I affix my signature.

JOHN R. CLOVER.
